(57) **CLAIM**

The ornamental design for a container cover, as shown and described.

DESCRIPTION

FIG. 1 is a top and side perspective view of my container cover according to a first embodiment of my new design;

FIG. 2 is a bottom and side perspective view thereof; FIG. 3 is a front elevation thereof, the rear view being a mirror image thereof;

FIG. 4 is a left elevation view thereof, the right view being a mirror image thereof;

FIG. 5 is a top plan view thereof;

FIG. 6 is a bottom plan view thereof;

FIG. 7 is a side elevation view thereof showing the container cover attached to an exemplary container bottom;

FIG. 8 is a top and side perspective view of my container cover according to a second embodiment of my new design;

FIG. 9 is a bottom and side perspective view thereof;

FIG. 10 is a front elevation thereof, the rear view being a mirror image thereof;

FIG. 11 is a left elevation view thereof, the right view being a mirror image thereof;

FIG. 12 is a top plan view thereof;

FIG. 13 is a bottom plan view thereof;

FIG. 14 is a side elevation view thereof showing the container cover attached to an exemplary container bottom;

FIG. 15 is a top and side perspective view of my container cover according to a third embodiment of my new design;

FIG. 16 is a bottom and side perspective view thereof;

FIG. 17 is a front elevation thereof, the rear view being a mirror image thereof;

FIG. 18 is a left elevation view thereof, the right view being a mirror image thereof;

FIG. 19 is a top plan view thereof;

FIG. 20 is a bottom plan view thereof;

FIG. 21 is a side elevation view thereof showing the container cover attached to an exemplary container bottom;

FIG. 22 is a top and side perspective view of my container cover according to a fourth embodiment of my new design;

FIG. 23 is a bottom and side perspective view thereof;

FIG. 24 is a front elevation thereof, the rear view being a mirror image thereof;

FIG. 25 is a left elevation view thereof, the right view being a mirror image thereof;

FIG. 26 is a top plan view thereof;

FIG. 27 is a bottom plan view thereof; and

FIG. 28 is a side elevation view thereof showing the container cover attached to an exemplary container bottom.

Shading represents contour only and not surface ornamentation.

(Continued)

The broken lines illustrate exemplary environment and form no part of the claimed design.
